UNITED STATES PATENT OFFICE

LYMAN C. REED, OF NEW ORLEANS, LOUISIANA

CIRCUIT-BREAKER

Application filed March 20, 1930. Serial No. 437,514.

This invention relates generally to apparatus for interrupting and protecting electric circuits and, more particularly, to certain new and useful improvements in such apparatus of the type known as circuit-breakers.

Heretofore, so far as I am aware, circuit-breakers employed for the purpose of protecting electrical systems against so-called overload and short-circuit conditions have been actuated by a spring operated mechanism which has a fixed time interval of circuit-opening response to such overload or short-circuit condition, such time interval being dependent wholly upon the strength of the spring and the weight of the parts moved thereby. In such cases, the flow of short-circuit current may often attain a magnitude approximately equal to the capacity of the system in which the short occurs and frequently causes the destruction of the circuit-breaker or some part thereof before the current-flow in the circuit is ruptured. The lost time occasioned by such fixed time-interval of rupture of the circuit is exceedingly important on overloads of the magnitude of short-circuits, not only because the heating of the separable contacts of the breaker is unnecessarily prolonged, but because the short-circuit current has the opportunity of growth to many times it would have if interrupted in a time-interval having a variable relation to the strength of initial current flow caused by the short-circuit.

However, even if the contacts be separated in such a current-responsive manner, opportunity may yet exist for growth of current-flow, due to the current-carrying capabilities of the occurring arc and the ionized air created thereby. And if a solid body of insulation material be interposed between the contacts for rupturing the arc, surface leakage around such body may occur tending to delay the actual rupture of the current-flow. Many auxiliary devices have been proposed for breaking the arc occurring on separation of the contacts, such as blow-out coils, de-ionizing plate assemblies, high-pressure-injected air, quenching liquids, and the like. Such agencies require an operating time-interval which is of appreciable magnitude compared

with the circuit-rupturing time-interval that may be employed without creating dangerous conditions in the circuit, and hence do not wholly suffice at all times to prevent serious disturbances in the line on occasion of heavy short circuits.

My present invention has hence for its objects the provision of an efficient circuit-breaking or interrupting apparatus for both A. C. and D. C. systems adapted for the solution of the various problems stated and the accomplishment in approximately the lowest possible time of the results sought.

And with the above and other objects in view, my invention resides in the novel features of form, construction, arrangement, and combination of parts hereinafter described and pointed out in the claims.

In the accompanying drawings (2 Sheets)—

Figure 1 is a side elevational view of a circuit-breaking apparatus of my invention, shown in circuit-opening position;

Figure 2 is a sectional view of the apparatus taken approximately along the line 2—2, Figure 1;

Figure 3 is a view of the apparatus similar to Figure 1, the several parts thereof, however, being shown in circuit-closing position, portions thereof being broken away and intermediate positions of some of the other parts being shown by dot-dash lines; and

Figure 4 is a view of the apparatus partly in plan and partly in section on approximately the line 4—4, Figure 3.

Referring now more in detail and by reference characters to the drawings, which illustrate a preferred embodiment of my invention, the circuit-breaker proper includes spaced front and back walls 1, 2, respectively, of suitable contour and preferably constructed of insulation material. Disposed transversely of the walls 1, 2, is a longitudinal partition A which includes a pair of overlapping slidable doors or engaging shutters 3, which, when closed, form an imperforate part of said partition for dividing the space between the walls 1, 2, into adjoining contact-chambers 4, 5, but which when opened provide an aperture communicating said chambers 4, 5, as soon appearing.

The shutters 3 are reciprocable in opposingly spaced jambs 6 also forming part of the partition A, each jamb 6 being provided with a shutter-receiving chamber 7 having one side wall extended beyond the other toward the short wall of the opposite chamber 7 of the other jamb 6. The overlapping margins of the shutters 3 are provided with openings or notches 8 each registrable in reversed relation with the other, so that, when the shutters 3 are opened, the bottom walls 9 of the notches 8 overtravel each other in the space between the jambs 6 to align the openings 8 for admitting through the so formed aperture the opposing engageable ends 10 of a pair of co-operable contact-members 11 of any suitable conducting material (Figure 4).

Each member 11 is laterally presented perpendicularly to the axis of a swingable substantially U-shaped contact-carrier 12 also of any suitable conducting material, the carriers 12 being oppositely pivoted for swinging their carried contacts 11 in inverted arcs which together form a reverse curve, along which the engageable ends 10 travel in opposed directions into and out of engagement for respectively closing and opening the circuit.

The legs of each member 12 terminate in oppositely presented axially aligned ears or pivot members 13 edgewise presented for standing in and rockably engaging aligned grooves 14 formed in the forked ends 15 of a horizontal supporting terminal member 16 also of conducting material. Each terminal member 16 is disposed preferably parallel with, but transversely and laterally spaced from the other and is suitably supported on, and with its end 15 projecting over the side of, one of a pair of diagonally spaced preferably rectangular insulation blocks 17, each fixed between the walls 1, 2, at opposite ends of the respective contact-chambers 4, 5.

A pin 18 is presented from a side of each block 17 in the plane of swingable actuation of the respective member 12 but oppositely to the pivotal axis thereof; and attached at an end to the pin 18, is a suitably elongated coiled spring or tensionally yieldable member 19 having its other end stretched past said pivotal axis and secured to a pin 20 fixed to and between the legs of the member 12 adjacent its upper end. The spring 19 is caused, on actuation of the member 12, to take a position alternately on opposite sides of the pivotal axis thereof. So arranged, the respective springs 19 and associated swingable members 12 co-operatively constitute a pair of toggles, which, when knuckled toward each other, act or function to engage the contacts 11 in circuit-closing position, as best seen in Figure 4.

When in circuit-closing position, each shutter 3 is disposed with its inner notched end guidingly engaged between the imper-

forate portion of the other shutter 3 and the margin of the adjacent long wall of the respective chamber 7. However, when the shutters 3 are actuated to circuit-opening position, as shown in Figure 2, the notched end of each shutter 3 moves into the adjacent chamber 7 and the imperforate portion moves partially out of the opposite chamber 7 into the space between the jambs 6 for closing the contact-aperture previously provided for the meeting ends 10 of the contact-members 11.

In closing the said contact-aperture, the walls 9 impinge the then presented ends of the contacts 11, which, yielding to such impingement, are initially actuated in circuit-opening direction, until the toggles are knuckled oppositely from their former positions, whereupon the toggles act with increasing force to acceleratively separate the contacts 11 in circuit-opening actuation thereof until brought to rest in widely spaced relation by each impinging the presented end of respective stops 21 supported for such purpose on the blocks 17. Such wide spacing of the contacts 11 is accompanied by an inward overlapping movement of the shutters 3 interposing an imperforate insulation wall between the contact-members 11 which electrically isolates each in its respective chambers 4, 5, and suppresses or breaks any occurring arc. The whole circuit-opening action is completed with a snapping action in such a short interval of time as to rupture the current flow and substantially abate the occurring arc before the same can grow to appreciable magnitude.

Surface creepage from the respective contacts 11 to the shutters 3 is prevented by the wide spacing of the contacts from the shutters, which establishes therebetween a substantial thickness of the dielectric fluid contained in the chambers 4, 5, whether the same be air, oil, an inert gas, or other suitable dielectric medium. The shutters 3 co-operating with the jamb walls 6 act to attenuate any occurring ionized air until it is unable to maintain the arc created on separation of the members 11, such arc being, so to speak, "snuffed out" by the shutters 3.

For closing the circuit, the shutters 3 are shifted or moved outwardly into the respective chambered jambs 6. A pin 22 is laterally presented from each shutter 3 into its adjacent chamber 4, 5. For each respective shutter 3, a spring or tensional member 23 has one end secured to the pin 22 and its other end to the eye-end of a bolt 24 which freely works through an aperture 25 provided in the respective member 11 and has an enlarged head 26 at its other end. When the shutters 3 are closed, each pin 22 moves toward its corresponding contact-member 11, causing the bolt 24 to project somewhat therebeyond; however, when the shutters 3 are opened, each pin 22 moves away from its corresponding

member 11, engaging the bolt 24 with the member 11 to thus oppose the tension of the spring 23 to that of the toggle spring 19.

The several parts are proportioned so that 5 shortly before the respective pin 22 impinges the adjacent short wall of the chamber 7, the force of the spring 23 will overcome that of the spring 19, knuckling the toggle of which the latter is a part in circuit-closing 10 direction. Both pairs of springs 19 and 23 then act to snap the contacts 11 into circuit-closing engagement through the aperture then provided by the now expanded shutters 3, Figure 4.

15 Straps 27, 28, are secured by a suitable fastening element 29 on opposite sides of the outer end of each shutter 3 with their laterally spaced ends presented into the respective jambs 6. Respective pins 30, supported 20 by and between the pairs of straps 27, 28, work in slots 31 formed in the end of respective levers 32, 33, each swingably presented through slots 34 provided in the wall 1 over each jamb 6. One lever 32 is longer than, 25 and swings oppositely to, the other lever 33. A relatively long bracket 35 is outwardly presented preferably from the top portion of the wall 1, the one lever 32 extending therealong and being pivoted at its outer end on 30 a pin 36 carried by the bracket 35. A relatively short bracket 37 is also outwardly presented from the approximately middle portion of the wall 1, the other lever 33 extending therepast and being pivoted intermediate 35 its ends on a pin 38 carried by the bracket 37.

Spaced parallel members constituting a link 39 are each pivoted at an end on a transverse pin 40 disposed intermediate the ends of the lever 32. Adjacent their other end, 40 the link-members 39 carry a cross-pin 41 adapted to work in a slot 42 provided in the outer end of the lever 33. Hence, when the link 39 is reciprocated, the levers 32, 33, are oppositely swung at their respective inner 45 end and simultaneously actuate the shutters 3 towards and away from each other for respectively closing or opening the contact-aperture adapted to be co-operably provided thereby.

50 Presented from the opposite side of bracket 35 and out of the plane of swingable actuation of the lever 32, is a pin 43, secured at an end to which is an elongated coiled spring or tensional member 44 having its other end 55 stretched past the pin 36 and secured to a pin 45 fixed on the lever 32 intermediate the pins 36 and 40, the pin 45 being presented for such purpose through a slot 46 provided in the bracket 35.

60 The spring 44 is caused, on actuation of the lever 32, to take a position alternately on opposite sides of the pivot pin 36 thereof. So arranged, the spring 44 and lever 32 co-operatively constitute a toggle, which when 65 knuckled in opposite directions acts to corre-

spondingly actuate its connected shutter 3, and reciprocate the link 39 for opposite actuation of the other shutter 3, such movements being limited by the impingement of the pin 45 with the opposite end-walls of the slot 46, the latter being adapted to limit or stop the lever 32 when the spring 44 is just past the pin 36 in shutter opening position for closing the circuit, so that a very small movement of the toggle will suffice to reversely knuckle 70 the same in shutter closing or circuit-opening direction, when the spring 44 acts with increasing force to acceleratively close the shutters 3 in a manner and at a speed corresponding to the circuit-opening actuation of the 80 contacts 11.

Thus the separable contacts 11 and closable shutters 3 are actuated by an operating means including tensionally responsive agencies caused to act with increasing force and speed for rupturing the circuit after a relatively small initial or tripping actuation thereof in circuit-opening direction.

Such small initial actuation may be accomplished responsively to current-flow in 90 the protected circuit by an automatic tripping mechanism which includes an electromagnet preferably comprising a pair of windings 47 mounted on a substantially U-shaped core 48 of suitable material, the yoke 95 thereof being engaged by means of suitable fastening elements 49 with a bracket 50 presented from the wall 1 at its lower portion, at which portion the wall 1 is preferably reinforced with a post 51 disposed between the 100 walls 1, 2. The legs of the core 48 are presented upwardly and terminate in horizontally aligned poles 52.

Electromagnetically associated with the 105 windings 47, is a swingable armature 53 having an end extending through a slot 54 in the wall 1 and pivoted on a pin 55 supported by a bracket 56 presented from the wall 2. Parallel arms 57 are upwardly presented from each side of the swingable end of the armature 53 and have aligned slots 58 in which works a transverse pin 59 carried by the adjacent lower end of the link 39. The pin 59 impinges the upper or outer end wall of the 110 registering slots 58 when the circuit-breaker is moved to circuit-closing position, the armature 53 being then suspended above and over the poles 52 with a relatively small air gap therebetween, as shown at 60 in Figure 3.

115 The leads 72, 73, of the circuit to be protected are suitably electrically connected to the terminals 16, 16, and leads 69, 70, serve to connect the windings 47 in the circuit, and I prefer to so connect the same that the abnormal current flow in the circuit provides the motivating force for actuation of the armature 53, whereby the latter is caused to 120 actuate the circuit-breaker in a time-interval proportional to the strength of the current-flow in the circuit protected. An inter-

mediate tap 71 serves to connect one winding 47 in series with the other and may also be employed for connecting the windings in parallel with the circuit, if desired.

5 The response of the armature 53 to current flow in the electromagnetic windings 47 is opposed by the force of the spring 44, which is constructed to yield at a predetermined or abnormal magnitude of current-flow selected 10 with a view of the maximum or short-circuit capacity of the system being protected.

On occurrence of such short-circuit or over-load, armature 53 responsive acts to set in motion the entire linkage connected thereto, 15 the air-gap 60 being selected to allow the armature 53 and initial actuating movement sufficient to reversely knuckle the toggle of which spring 44 is a part, and at substantially the same time to also reversely knuckle the 20 toggles constituted by the contacts 11 and springs 19, the pin 59 disengaging the wall of the slots 58 as the link 39 continues in motion after the armature 53 seats on the pols 52.

25 The apparatus also includes a manually manipulative actuating mechanism for closing the circuit-breaker, which comprises means for rendering the tripping means trip-free or operable independently of the actuating means. For such purpose, the lever 32 is provided with a substantially rhomboidal aperture 61, the upper wall *a* of which is inclined from the lower wall *b* thereof, so that the aperture 61 is wider at its front wall 30 *c* than at its rear wall *d*. A shiftable latch or lever 62 is pivoted at its lower end on an outwardly presented lever or handle 63 swingable on a pin 64 presented from the bracket 35 and conveniently projecting 35 through a slot 65 provided in the link 39. The latch 62 carries at its swingable end a finger or detent 66 laterally presented in the aperture 61 for alternately impinging the several walls thereof. On actuation of the 40 handle 63, the detent 66 shifts correspondingly in the aperture 61. The latch 62 is also swingable on the handle 63 and urged thereto by a spring or tensional member 67 having its opposite ends suitably engaging the latch 45 62 and the handle 63, respectively.

45 On upward swinging of the handle 63 from "off" or circuit-opening position to "on" or circuit-closing position, corresponding to like positions of the contacts 11, the latch 62 advancingly engages its detent 66 with the aperture-walls *a*, *d*, at their corner and is frictionally held thereto by the opposition of the spring 44 while so advancing, as shown by dot-dash lines in Figure 1, until the toggle of 50 which spring 44 is a part is reversely knuckled in circuit-closing direction. Thereupon, the detent 66 is disengaged from the aperture-walls *a*, *d*, the spring 67 swinging the latch 62 until the detent 66 impinges the opposite corner 55 of the aperture 61 formed by its walls

b, *c*, thereby rendering the lever 32 trip-free of the handle 63, Figure 1.

On circuit-opening actuation of the circuit-breaker proper, the lever 32 moves independently of the latch 62 by reason of the clearance between the top wall *a* and bottom wall *b*. As this movement is completed, a stop-pin 68 presented from the bracket 35 de-pressingly engages a cam-face *e* on the latch 62 for clamping or locking the detent 66 into impingement with the walls *a*, *d*, at their corner, thereby restoring the latch 62 to actuating position, the final portion of such movement of the lever 32 being imparted to the latch 62 for correspondingly returning the handle 63 to "off" position.

Thus there is an intermediate circuit-opening position of the lever 32 to which it may be "tripped" when the handle 63 is in its "on" position, such position being obtained when attempting to close the circuit-breaker against a continuing abnormal condition in the protected circuit. From its "on" position, however, the handle 63 may be manually or otherwise swung downwardly, the detent 66 engaging the wall *b* for actuation of the lever 32 in circuit-opening movement until the toggle is broken in that direction, when the spring 44 acts to complete the movement, as above described.

55 The apparatus provides for a circuit-rupturing mechanism adapted especially, though not exclusively, for use with high voltages, and comprises simultaneously movable parts which by their coaction interrupt the circuit in half the time required by either of them alone. Such result accrues by reason of the fact that the circuit-rupturing time interval is a function of the relative speed of the moving parts, and if these parts move simultaneously in opposite directions their relative speed is twice that obtained by their individual actuation.

60 The design characteristics and assembly of the apparatus are typical for various voltages and current capacity; the distances between parts of opposite polarity and the thickness of the dielectric are proportional to the voltage to be broken. The apparatus is capable of breaking successfully any commercial voltage in air or other fluid dielectrics with a minimum disturbance in the line and at such high speeds that no appreciable thermal effect is noticeable in the operating parts. The circuit-rupturing actuation of the circuit-breaker is automatically effected responsive to flow of current in the protected circuit and occurs with an initial operating movement applied directly to the shutters 3 and contacts 11, which movement so started is completed by the momentum of the moving parts and tensionally responsive means acting with increasing force to move the parts at a speed much greater than could be effected by the current-responsive means acting alone. The 65

current-responsive means initially actuates the arc-rupturing shutters, which, in turn, impingingly actuate the contacts in circuit-rupturing direction. In such manner, the 5 number of moving parts required is reduced to a minimum, with consequent greater speed of the parts due to a given accelerating force.

I may add that, in actual practice, a circuit-breaker constructed according to my invention to carry a voltage of 13800 volts broke a large number of dead short circuits at such voltage without a failure, using air as the fluid dielectric.

It is to be understood that changes and 10 modifications in the form, construction, arrangement, and combination of the several parts of the circuit-breaker and its associated instrumentalities may be made and substituted for those herein shown and described without departing from the nature and principle 20 of my invention.

Having thus described my invention, what I claim and desire to secure by Letters Patent is:

25 1. In an electric circuit-breaker, in combination, co-operable contact-members, and means for engaging and disengaging said members for respectively closing and opening the circuit, said means including opposed 30 shiftable insulation-members for co-operably electrically isolating the contact-members one from the other when in circuit-opening position.

2. In an electric circuit-breaker, in combination, co-operable contact-members, and means for engaging and disengaging said members for respectively closing and opening the circuit, said means including a pair of opposed insulation walls oppositely shift- 40 able for co-operably electrically isolating the contact-members one from the other when in circuit-opening position.

3. In an electric circuit-breaker, in combination, co-operable contact-members, 45 mechanism for engaging said members for closing the circuit, and means for disengaging said members for opening the circuit, said mechanism including a pair of opposed insulation walls oppositely shiftable for co- 50 operably electrically isolating the contact-members one from the other when in circuit-opening position.

4. In an electric circuit-breaker, in combination, co-operable contact-members, 55 mechanism for engaging said members for closing the circuit, and means for disengaging said members for opening the circuit, said mechanism including a pair of opposed shiftable insulation walls having connection with 60 the contact-members, and means for shifting said walls, said walls when in circuit opening position being interposed between the contact-members for electrically isolating the same one from the other.

65 5. In an electrical circuit-breaker, in com-

bination, co-operable contact-members, toggle means for normally swingably retaining said members in circuit-opening position, a pair of opposed shiftable insulation walls having yielding connection with the contact-members, and means for shifting said walls, said walls on one movement actuating said toggle means for engaging the contact-members for closing the circuit and on reverse movement permitting disengagement of the contact-members for opening the circuit, said walls being interposed between the contact-members on circuit-opening movement thereof for electrically isolating the same one from the other.

6. In an electrical circuit-breaker, in combination, co-operable contact-members, spring toggle means for normally swingably retaining said members yieldingly in circuit-opening position, a pair of opposed shiftable insulation walls having yielding connection with the contact-members, and means for shifting said walls, said walls on one movement engaging the contact-members against the pull of said toggle means for closing the circuit and on reverse movement permitting disengagement of the contact-members for opening the circuit, said walls being interposed between the contact-members on circuit-opening movement thereof for electrically isolating the same one from the other.

7. In an electrical circuit-breaker, in combination, co-operable contact-members, spring toggle means for normally swingably retaining said members yieldingly in circuit-opening position, a pair of opposed shiftable insulation walls having yielding connection with the contact-members, and spring-linkage-toggle means for shifting said walls, said walls on one movement engaging the contact-members against the pull of the first toggle means for closing the circuit and on reverse movement permitting disengagement of the contact-members for opening the circuit, said walls being interposed between the contact-members on circuit-opening movement thereof for electrically isolating the same one from the other.

8. In an electrical circuit-breaker, in combination, co-operable contact-members, spring-toggle means for normally swingably retaining said members yieldingly in circuit-opening position, a pair of opposed shiftable insulation walls having yielding connection with the contact-members, spring-linkage-toggle means for shifting said walls, said walls on one movement engaging the contact-members against the pull of the first toggle means for closing the circuit and on reverse movement permitting disengagement of the contact-members for opening the circuit, said walls being interposed between the contact-members on circuit-opening movement thereof for electrically isolating the same one from the other, and means respon-

- 5 sive to current-flow for initiating movement of said walls to circuit-opening position.
9. In an electrical circuit-breaker, in combination, co-operable contact-members, 5 spring-toggle means for normally swingably retaining said members yieldingly in circuit-opening position, a pair of opposed shiftable insulation walls having yielding connection with the contact-members, spring-linkage-toggle means for shifting said walls, said walls on one movement engaging the contact-members against the pull of the first toggle means for closing the circuit and on reverse movement first impinging the contact-members for initiating and then permitting full disengagement of the contact-members for opening the circuit, said walls being interposed between the contact-members on circuit-opening movement thereof for electrically isolating the same one from the other, and means responsive to current flow for initiating movement of said walls to circuit-opening position.
10. In an electric circuit-breaker, in combination, co-operable contact-members, mechanisms for engaging said members for closing the circuit, means for disengaging said members for opening the circuit, said mechanism including a pair of opposed shiftable insulation walls having connection with the contact-members, and means for shifting said walls, said walls when in circuit opening position being interposed between the contact-members for electrically isolating the same one from the other, and means responsive to current flow for automatically initiating movement of said walls to circuit-opening position.
11. In an electrical circuit-breaker, in combination, co-operable contact-members, spring toggle means for normally swingably retaining said members yieldingly in circuit-opening position, a pair of opposed shiftable insulation walls having yielding connection with the contact-members, and means for shifting said walls, said walls on one movement engaging the contact-members against the pull of said toggle means for closing the circuit and on reverse movement permitting disengagement of the contact-members for opening the circuit, said walls being interposed between the contact-members on circuit-opening movement thereof for electrically isolating the same one from the other, and means responsive to current flow for automatically initiating movement of said walls to circuit-opening position.
12. In an electric circuit-breaker, in combination, co-operably engageable contact-members, means for disengaging said members for opening the circuit, and a pair of opposed insulation walls oppositely shiftable for co-operably electrically isolating the contact-members one from the other when in circuit-opening position.
13. In an electric circuit-breaker, in combination, co-operably engageable contact-members, spring-toggle means for disengaging said members for opening the circuit, and a pair of opposed insulation walls oppositely shiftable for electrically isolating the contact-members one from the other when in circuit-opening position, said walls having connection with the contact-members for yieldingly retaining the same in circuit-closing engagement against the pull of said toggle-means.
14. In an electric circuit-breaker, in combination, co-operably engageable contact-members, spring-toggle means for disengaging said members for opening the circuit, and a pair of opposed insulation walls oppositely shiftable for electrically isolating the contact-members one from the other when in circuit-opening position, said walls having connection with the contact-members for yieldingly retaining the same in circuit-closing engagement, and means for shifting said walls to circuit-opening position, said walls being engageable with the contact-members on movement to circuit-opening position for initiating circuit-opening movement thereof.
15. In an electric circuit-breaker, in combination, a pair of opposed spring toggles each comprising a respective pivoted carrier, contact-members mounted on the carriers and normally in yielding circuit-opening disengagement, a pair of relatively shiftable insulation members having yielding connection with the contact-members, and means for actuating the shiftable members for effecting circuit-closing engagement of the contact-members, said walls being interposed between the contact-members on movement thereof to circuit opening position for electrically isolating the same one from the other.
16. In an electric circuit-breaker, in combination, a pair of opposed spring toggles each comprising a respective pivoted carrier, contact-members mounted on the carriers and normally in yielding circuit-opening disengagement, a pair of relatively shiftable insulation members having yielding connection with the contact members, and means for actuating the shiftable members for effecting circuit-closing engagement of the contact-members against the pull of said toggles, said walls being adapted on movement thereof to circuit-opening position for impingement with the contact-members for initiating circuit-opening movement thereof and being then interposed between the contact-members for isolating the same electrically one from the other.
17. In an electric circuit-breaker, co-operable contact-members adapted for separation to open the circuit, means including a pair of closable shutters adapted on closing movement thereof to actuate said contact-members in circuit-opening direction, and

other means including a member operable responsive to current-flow in the circuit for actuating said shutters.

18. In an electric circuit-breaker, co-operative contact-members adapted for separation to open the circuit, means including a pair of closable shutters adapted on closing movement thereof to actuate said contact-members in circuit-opening direction, means responsive to flow of current in the circuit for initial actuation of said shutters, and means including a tensional member adapted to act with increasing force for assisting actuation of said shutters.

19. In an automatic circuit-breaker, a pair of shiftable shutters, a pair of engageable contacts actuatable by said shutters, and electro-responsive means for actuating said shutters in one direction.

20. In an automatic circuit-breaker, a pair of shiftable shutters, a pair of engageable contacts actuatable by said shutters into and out of engagement for respectively closing and opening the circuit, and electro-responsive means for actuating said shutters in one direction for opening the circuit.

21. In an automatic circuit-breaker, a pair of shiftable shutters, a pair of engageable contacts actuatable by the shutters into and out of engagement for respectively closing and opening the circuit, and mechanism for actuating the shutters into circuit-closing position and for rendering the shutters trip-free when the contacts are engaged.

22. In an automatic circuit-breaker, a pair of shiftable shutters, a pair of engageable contacts actuatable by the shutters into and out of engagement for respectively closing and opening the circuit, and means including a lever and a latch alternately swingable on the lever for actuating said shutters into circuit-closing position and for rendering the shutters trip-free when the contacts are engaged.

23. In an automatic circuit-breaker, a pair of shiftable shutters, a pair of engageable contacts actuatable by the shutters into and out of engagement for respectively closing and opening the circuit, means including a lever and a latch alternately swingable on the lever for actuating said shutters into circuit-closing position and for rendering the shutters trip-free when the contact-members are engaged, and means for restoring said latch to actuating position.

24. In an automatic circuit-breaker, a pair of shiftable shutters, a pair of engageable contacts actuatable by said shutters, and means responsive to flow of current in the circuit having operative connection with said shutters.

25. In an automatic circuit-breaker, a pair of shiftable shutters, a pair of engageable contacts actuatable by said shutters, and means including an armature responsive to flow of current in the circuit having a disengageable

operative connection with said shutters for actuating the same in one direction.

In testimony whereof, I have signed my name to this specification.
